UNITED STATES PATENT OFFICE.

EDWARD ALBERT FARR, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A PERCOLATOR URN OR SIMILAR ARTICLE.

Application filed February 2, 1923. Serial No. 5,053. Term of patent 14 years.

To all whom it may concern:

Be it known that I, EDWARD A. FARR, a citizen of the United States, residing at Meriden, county of New Haven, and State of Connecticut, have invented a new and original and ornamental Design for a Percolator Urn or Similar Article, of which the following is a specification, reference being

had to the accompanying drawing, forming a part thereof.

The figure is a perspective view of a percolator urn showing my new design.

I claim:

The ornamental design for a percolator urn or similar article as shown.

EDWARD ALBERT FARR.
